UNITED STATES PATENT OFFICE

JOHN J. FRANK, OF PITTSFIELD, MASSACHUSETTS, ASSIGNOR TO GENERAL ELECTRIC COMPANY, A CORPORATION OF NEW YORK

ELECTRIC FURNACE

Application filed December 21, 1927. Serial No. 241,682.

My invention relates to electric furnaces and has for its object the provision of an improved arrangement of conductors whereby the reactance of the furnace electric circuit is reduced.

My invention has especial application to furnaces employing comparatively large currents of the magnitude, for example, of ten to twenty thousand amperes, such as are used in electric smelting furnaces. With such large currents the reactance of the furnace circuit has an important effect on the operation of the generating equipment, the least possible reactance being desirable in order that the furnace load will have the most favorable power factor.

In carrying out my invention I employ a special arrangement of bus bars leading to the furnace terminals, the electrical connection with the terminal most remote with respect to the supply source being effected by means of a plurality of conductors or bus bars electrically connected in parallel and arranged in close proximity to the furnace structure on various sides thereof.

For a more complete understanding of my invention reference should be had to the accompanying drawing the single figure of which is a more or less diagrammatic side elevation view partly in section of an electrode furnace embodying my invention.

Referring to the drawing, I have shown my invention in one form as applied to a furnace of the electrode type although it will be understood that my invention is applicable to various other types of furnaces, such as those employing a heating resistor element, in which it is desirable to reduce the reactance of the furnace circuit. The furnace comprises an elongated crucible 10 made of suitable heat refractory material forming a receptacle for the molten metal 11. Extending through the walls of the receptacle at points above the level of the metal and at opposite ends of the receptacle are two elec-

trodes 12 and 13. These electrodes are inclined downward toward the interior of the receptacle and are arranged to be in arcing relation with the charge, or they may be in arcing relation with each other. The molten charge can be withdrawn from the bottom of the receptacle through a tap opening 14. A heat insulating cover 15 is preferably provided for the crucible.

Electric current is supplied to the electrodes from a suitable alternating current supply source of low voltage, such as the secondary of the transformer 16, the electrical connections being made through bus bars 17 and 18 which are of large cross sectional area in order that they may carry the relatively large currents required, which may be as high as 20,000 amperes or more, depending of course upon the capacity of the furnace. The bus bar 18 is led directly to the nearer electrode 13, i. e., the electrode which is nearer the transformer 16 or otherwise more easily accessible for the electrical connections. It will be understood that with the relatively heavy currents involved the electrical connections are made as short as possible in order to keep both the resistance and the inductance of the circuit at a minimum value.

For the purpose of reducing the reactance of the circuit, more particularly the inductance of the circuit, the bus bar 17 is connected to the more remote electrode 12 through a plurality of bus bars 19, 20, 21 and 22 electrically connected in parallel, which extend lengthwise in close proximity with the top, bottom and opposite sides of the furnace respectively. The bus bar 17 is electrically connected to these bus bars through an intermediate connecting bus bar 23 which is connected to the ends of the bus bars 19 to 22 inclusive. The opposite ends of these bus bars are electrically connected to the electrode 12. The bus bars 19—22 inclusive are of relatively small cross sectional area as compared with the bus bar 17, their combined cur-

rent carrying capacity being equal to that of the bus bar 17. Preferably, however, they are of relatively great width with respect to the top, bottom and sides of the crucible with correspondingly reduced thickness.

5 I have found that this distribution of the conductors or bus bars with respect to the furnace walls very greatly reduces the reactance of the furnace circuit as compared with the reactance with the usual connections 10 in which the bus bar 17 would be extended and connected directly to the electrode 12. In fact, the reactance with the arrangement shown may be only a fractional part of the 15 reactance with the usual arrangement.

15 Since the bus bar 19 extends over the top of the furnace, it will be necessary to remove the cover 15 by moving it sidewise after it has been lifted somewhat. Any suitable arrangement can be used in order to provide for 20 charging the furnace. The bus bar 19 may be omitted entirely, for example, in which case only three auxiliary bus bars would be provided and the reactance of the circuit 25 would still be found to be greatly reduced.

25 While I have described my invention as embodied in concrete form and as operating in a specific manner in accordance with the provisions of the patent statutes, it should be 30 understood that I do not limit my invention thereto since various modifications thereof will suggest themselves to those skilled in the art without departing from the spirit of my invention, the scope of which is set forth in 35 the annexed claims.

What I claim as new and desire to secure by Letters Patent of the United States, is:

1. The combination with an electric furnace, of electrical connections for a single 40 terminal of said furnace comprising a plurality of conductors distributed along a plurality of the walls of said furnace in close proximity thereto.

2. The combination with an electric furnace, of connections therefor comprising a 45 bus bar connected directly to one electrode and a plurality of bus bars connected to the other electrode, said plurality of bus bars being arranged lengthwise in close proximity to a plurality of the walls of said furnace.

3. The combination with an electric furnace, of connections therefor comprising a 55 plurality of bus bars, electrical connections between one of said bus bars and the more easily accessible electrode and electrical connections between the other bus bar and the more remote electrode, comprising a plurality of bus bars of relatively small cross section extending lengthwise in close proximity to a plurality of the walls of said furnace so as to reduce the inductance of the circuit for 60 said furnace.

4. The combination with an electric furnace, of an electric supply circuit therefor

including an electrical supply source and a plurality of electrical conductors leading from at least one terminal of said supply source to one terminal of said furnace, said conductors being distributed in close proximity to a plurality of the top, bottom and side walls of said furnace so as to reduce the inductance of said circuit. 70

In witness whereof, I have hereunto set my hand this 19th day of Dec., 1927. 75

JOHN J. FRANK.
